UNITED STATES PATENT OFFICE.

BERT W. FLANDERS, OF NEW LONDON, CONNECTICUT, ASSIGNOR TO THE NEW LONDON CHEMICAL COMPANY, OF NEW LONDON, CONNECTICUT, A CORPORATION OF CONNECTICUT.

DEODORIZER.

1,309,619.

Specification of Letters Patent. Patented July 15, 1919.

Application filed March 8, 1918, Serial No. 221,238. Renewed November 23, 1918. Serial No. 263,946.

To all whom it may concern:

Be it known that I, BERT W. FLANDERS, a citizen of the United States, residing at New London, in the county of New London and 5 State of Connecticut, have invented new and useful Improvements in Deodorizers, of which the following is a specification.

This invention relates to deodorizers or air purifiers in which a suitable disinfectant 10 or deodorant is contained in a receptacle from which it is fed to the atmosphere for the purpose of purifying the latter.

In this class of device when used in theaters and public halls or other places of 15 amusement, the device may be placed in the path of a current of air furnished from a fan or blower, so that the contents of the receptacle will be distributed throughout the hall or auditorium. This device works well 20 during the summer months, but owing to the excessive heat to which the device is subject during the winter months, the liquid frequently reaches a boiling point. This causes rapid evaporation and has a tendency to 25 change the odor of the liquid, rendering the device expensive in operation and unsatisfactory in results.

For the purpose of overcoming these disadvantages the present invention comprehends the provision of an insulator which surrounds the receptacle and which may be in the form of a vacuum chamber or any other suitable insulating means, such as an asbestos covering, mineral wool packing or 35 the like.

The present invention is designed as an improvement on an application filed by me October 6, 1917, Serial No. 195,144, which application is at present pending and the 40 improvement will be herein described in connection with the subject matter shown in the said application, although it is apparent that the devices of different structure may be substituted, the present invention as 45 above stated covering the conservation of the contents of the device through suitable insulation.

In the drawings:

Figure 1 is a perspective view of one embodiment of the invention;

Fig. 2 is a transverse sectional view of the same; and

Fig. 3 is a detailed perspective view of the wick supporting frame.

55 Referring to the drawings in detail the in-

vention includes a receptacle comprising outer and inner walls 10 and 11, the said walls being suitably spaced apart to provide a vacuum space or chamber 12.

The inner wall forms a receptacle for a 60 suitable deodorizer or disinfectant and is provided with a longitudinally disposed slot 13, which is aligned with a slot 14 formed in the outer wall 11, the edges of these slots being connected by walls 15, which form a 65 passage 16. A suitable filling opening 17 communicates with the interior of the receptacle and is closed by a cap 18.

As in the before mentioned application there is provided a frame which includes 70 channeled side bars 19 and a yoke 20, the side arms of the latter passing through the channel bars 19 and the frame inserted through the passage 16 after the manner of the frame described in connection with my 75 co-pending application. Stops 21 extending inwardly from the bottom of the receptacle are located for contact with the yoke 20, while springs 22 carried by the outer wall of the receptacle bear against the side bars 19 80 to hold the yoke 20 in such contact.

Located within the frame just described is a folder 23 composed of two leaves of reticulated metal, for example wire gauze, these leaves being united at their outer edges 85 as by bending and their size being such as to fill the space between the bar 19 with their edges within the channels of the latter. Within this folder is positioned a wick 24 of any suitable fabric, preferably cheese 90 cloth or other soft and porous material, the wick being of sufficient length to extend within the receptacle and into the liquid contained therein.

As previously pointed out the novelty of 95 the invention resides in a protecting insulation for the contents of the receptacle, which in the present instance is shown in the form of the chamber 12. The outer wall 10 of this chamber is equipped with a vacuum 100 valve 25, by means of which the air may be exhausted from the chamber. Supporting legs 26 are also secured to the outer wall of the chamber 12 which permits of the device being placed upon the floor of ducts or conduits, so that the air will pass through the wick and distribute the contents of the receptacle.

It is believed that the foregoing description when taken in connection with the ac- 110

companying drawings, will render the construction, operation and advantages of the invention apparent. The right is reserved to make any and all changes as will properly fall within the scope of the appended claims.

Having described the invention what is claimed; is:—

10. The herein described deodorizer comprising a horizontally disposed tank or receptacle, an insulating wall surrounding said receptacle, said wall being formed with a longitudinally disposed slot establishing communication between the interior of the receptacle and the atmosphere, and means 15 extending through said slot for feeding the contents of the receptacle to the atmosphere.
20. The herein described deodorizer comprising a horizontally disposed tank or receptacle, an insulating chamber surrounding said receptacle, a passage extending longitudinally of the receptacle through said cham-

ber to establish communication between the interior of the receptacle and the atmosphere, and means extending through said passage for feeding the contents of the receptacle to the atmosphere. 25

3. The herein described deodorizer comprising a horizontally disposed tank or receptacle, said receptacle including inner and outer cylinders spaced apart to provide insulating air chambers, said cylinders being formed with longitudinally extending registering slots, a wall connecting said slots and defining a longitudinally extending passage establishing communication between the interior of the receptacle and the atmosphere and means extending through said passage for feeding the contents of the receptacle to the atmosphere. 30 35

In testimony whereof I affix my signature. 40

BERT. W. FLANDERS.
